UNITED STATES PATENT OFFICE.

SAMUEL W. MEAD, OF WESTON, MASSACHUSETTS.

AIR VENTILATION SYSTEM.

1,324,059.

Specification of Letters Patent.

Patented Dec. 9, 1919.

Application filed September 20, 1917. Serial No. 192,236.

To all whom it may concern:

Be it known that I, SAMUEL W. MEAD, citizen of the United States, residing at Weston, in the county of Middlesex and State of Massachusetts, have invented certain new and useful Improvements in Air Ventilation Systems, of which the following is a specification, reference being had thereto in the accompanying drawings.

10 My invention relates particularly to means for ventilating two or more rooms, superimposed, of a building for congregations of people, say students, or hospital patients; and, at the same time, providing 15 a building wherein are the fulfilled requirements of hygiene, safety, economy of space, and economy in administration.

My invention may best be explained when applied to school buildings.

20 The present box-like classrooms with their forced heat and vents, serving the congregation of forty or fifty children in a room, are faulty, in that, for example, when fresh air comes into a room through a duct 25 and a register in the wall of a room, and the foul air goes out through another register, the perfect freedom of movement of both incoming and outgoing air is interfered with, as by the formation of eddies 30 or dead air spaces, in the corners of the room; and because of them, the foul air tends to remain in these eddies to the detriment of the freedom of flowage of all of the air directly to the outlet. Any system of 35 ventilation dependent upon air ducts and registers is found to have these, as well as other well-known resulting objectionable features. Consequently a demand for out-of-door conditions in the classroom is heard 40 from educators, to overcome the lack of efficient work of students, due to poor ventilation.

It has been demonstrated in industrial buildings, where hundreds of people are employed and great efficiency of labor has been obtained, that almost out-of-door conditions may be brought about by the use of the "monitor" roof as a circulator of the air. Now the object of my invention is, primarily, 45 so to plan and arrange a building of more than one story in height, that in each room, there may be enjoyed the benefits resulting from the use of a "monitor" ventilator;

and, incidentally, that there may be a complete economical utilization of the cubical 55 contents of the congregation rooms and corridors.

By the term "monitor" roof or ventilator is meant a raised central portion of the roof, or the ceiling of a room, of a building, with windows or open spaces in the sides thereof, through which air in the room may rise and escape.

In the drawings illustrating the principle of my invention and the best mode now 65 known to me of embodying the same in operative structure,

Figure 1 is a perspective view of my invention embodied in a number of stories of a typical unit or bay of a schoolhouse 70 showing "monitor" ventilators, corridors, and recreation loggia;

Fig. 2 is a transverse section on line 2—2, Figs. 3 and 4;

Fig. 3 is a horizontal section, on line 3—3, 75 Fig. 2;

Fig. 4 is also a like section, on line 4—4, Fig. 2;

Fig. 5 is an enlarged detail of my invention to show more clearly its construction 80 and the arrow indicates air currents;

Figs. 6 and 7 show how indirect heating may be used in connection with my invention.

A typical unit or bay of a school building 85 has two or more stories, 1, 2, Figs. 1 and 2, the floors 4 and 5, of which are supported by piers 6, girders 7 and curtain walls 8.

In ground plan, each floor is divided up into a congregation or classroom 9, Fig. 3, 90 a corridor 10, and a wardrobe 11; suitable doorways 12, 13, connect the classroom with the corridors and the wardrobe; and windows 14, in the lower part of the curtain walls, open the classroom to the outside air. 95

The space in each story between the floor, as 4, of the corridor 10 and the main floor, as 5, above, is subdivided horizontally by a mezzanine floor 15, while the whole story height over the floor 4 of the classroom 9, 100 is occupied by the classroom, and a sloping ceiling or roof 16 springing from the four walls of the room at the mezzanine floor 15, and terminating in a "monitor" ventilator 17, having movable windows or slides 18. 105 Projecting inwardly from all sides of the

"monitor" ventilator, in the plane of the ceiling or roof of the schoolroom, is an air-controlling lip or shelf 19, Figs. 4 and 5, the outer edge 20, Fig. 5, of which constitutes 5 the air outlet of the schoolroom.

The curtain walls between the mezzanine floor, as 15, and the main floor, as 6, above, are removed to an extent to form large openings 21 to the outside air, between all of 10 the piers 7. Great air channels are thus formed by the mezzanine floor 15, Figs. 1 and 2, and the classroom ceiling or roof 16, and the school floor 6 above, and lead to and from the "monitor" ventilator 17 of the 15 classroom; thus offering practically no obstruction to the flowage and presence of unlimited outside air, and at the same time, turning the mezzanine story into an open loggia 22, accessible from the classroom by 20 a staircase 23, Fig. 3, and perfectly adapted to out-of-door school recreation purposes.

Outside air may enter the corridors 10 in the usual manner, as by windows 24, as shown in Figs. 1 and 2.

25 My invention does not depend upon artificial heating of the air. It relies upon the natural currents of outside air, and the warm air arising from a congregation of people, and is embodied in a form which attempts 30 to permit the greatest freedom of movement of such currents.

In warm weather no artificial heating is needed for physical comfort, but when it is necessary, either direct or indirect heating 35 may be economically and easily applied to my system. Fig. 5 shows sets of piping required for direct heating, one set 30 passing around the room below the windows 14, while the other 31, lies adjacent to the lip 19 40 opening into the "monitor" ventilator 17, to aid in circulating the up and the down currents due to the ventilator. In the case of indirect heating, see Fig. 6, the incoming air, before entering the room, through the 45 floor 32, is heated by a coil of piping 33 in an air channel 34, say in the top portion of the "monitor" of the room below; or by piping 35, Fig. 7, in an air box 36, which receives outside air from the outside loggia below, 50 and discharges it up through the floor, at the sides of the schoolroom. As in the case of direct heating, so in the case of indirect heating, a coil of piping 37 lies adjacent to the air outlet in the ceiling of the room.

55 From this description of the physical structure, including references to the drawings, the operation of my invention must be plain. Outside air freely enters the schoolroom through open windows, doors, or openings in the wall. It becomes heated either by the presence of the people, by artificial means, or by both, and rises, the walls and ceiling guiding it up through the lip opening into the "monitor" ventilator. Here it 60 is met by cross currents of outside air flow-

ing in any one direction between the mezzanine floor and the floor above, to, through and away from, the "monitor" ventilator, and is swept away; the tendency to forming a vacuum in the upper part of the room, 70 producing a continuous current of outside air flowing into, up through, and out of the room. Some of the outside air entering the "monitor" ventilator through its windows or dampers, tends to form a down draft into 75 the schoolroom, but this is overcome by the lip and the rising air from the room, which causes said outside air to assume a whirling course, as indicated in Fig. 5, whereby said air is thrown across, and out of, the "monitor," rather than down into the room. In short, the currents of outside air as developed, for example in a chimney, are approximated as nearly as possible in the air currents formed in relation to rooms, superimposed one upon another. 80

The general clear story height in a school building is thirteen feet, but to make use of my invention, it is desirable to increase this to approximately fifteen feet, so that each 90 story is capable of the above-mentioned subdivision.

With this horizontal subdivision, it is plain, in conclusion, that the lower division is kept to its original planning of corridor, classroom and wardrobe; and the upper division of the class or work room, to the forming of the "monitor" ventilator; while the division of over the corridor serves for out-of-door recreation. Obviously, the lower division retains the ideal indoors school administrative conditions; and the upper division gives the ideal ventilation of the classroom, and the complete out-of-door conditions for drill or recreation, planned for 100 each schoolroom as a unit.

Further, it appears that the cubical contents of the room and corridor have been fully utilized; and also that a like subdivision of the clear story height of an adjacent wardrobe, can be taken advantage of; 110 the upper subdivision 40, Fig. 4, serving as a perfect arrangement of the toilets for the schoolroom; and the lower, for a coat room; both being ample in height, connected by 115 stairways, and accessible to the recreation corridor and the schoolroom. By this construction, the teacher has complete supervision over her unitary schoolroom, wardrobe, toilets, corridor and recreation corridor.

It will also be seen that all of what would otherwise be expensive curtain walls for this upper division, have been reduced to less costly piers, thereby forming a loggia to 125 house the "monitor" ventilator; and out of the spaces that would otherwise be waste height in corridor, wardrobe and schoolroom, have resulted in great open air spaces and channels for my ventilating system. 130

Still further, while the old system of heating and ventilating involves great expense for mechanical equipment and air ducts, located in the basement, and walls of the building; by the use of my invention, the heating, when required, may be accomplished by the ordinary system of piping for direct radiation; and the space in the basement formerly occupied by this mechanical equipment, may now be utilized for purposes other than heating and ventilating.

Having described the structure and operation of my invention, and desiring to protect the same in the broadest manner legally possible, what I claim is:

1. A building structure embodying main walls, and divided horizontally by floors to provide alternately-arranged closed living-apartment-sections and permanently-open recreation-sections, both of said sections extending from one main wall to another, and ventilators extending upwardly from each of said apartment-sections into the recreation-section above and lying in the path of the currents of air passing through the per-

manently-open recreation-section, for the purpose set forth.

2. A building structure divided into stories, each story being divided horizontally by sub-floors to provide a lower closable living-apartment-section and an upper column-section permanently open at its sides and throughout its area to the atmosphere, a portion of said sub-floors being inclined upwardly into said upper column-section to form an inclined ceiling for the apartment below, a ventilator at the apex of said inclined portions of the sub-floors and projecting above the same to lie in the path of the currents of air passing through said column-section, and said column-sections of the structure being of sufficient height to provide a recreation-space for the occupants of the closable apartment below.

In testimony whereof I affix my signature in presence of two witnesses.

SAMUEL W. MEAD.
